UNITED STATES PATENT OFFICE.

CLINTON A. TOWER, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

SPECIFICATION forming part of Letters Patent No. 728,182, dated May 12, 1903.
Application filed May 29, 1902. Serial No. 109,477. (No model.)

To all whom it may concern:

Be it known that I, CLINTON A. TOWER, of Cleveland, Cuyahoga county, Ohio, have invented a new and useful Car-Coupler, of which the following is a full, clear, and exact description, reference being had to the accompanying drawings, forming part of this specification, in which—

Figure 1 is a plan view of two coupler-heads A B having my improved devices shown in locked position, one of the coupler-heads being partly in horizontal section for purposes of illustration. Fig. 2 is a vertical longitudinal section on the line II II of Fig. 1, the coupler A being shown with its locking and opening piece in lock-set position and the other coupler, B, being shown with its locking and opening piece in locked position. Fig. 3 is a horizontal section of one of my improved couplers having its knuckle thrown forward. Fig. 4 is a vertical cross-section on the line IV IV of Fig. 3. Fig. 5 is a vertical section showing the locking and opening piece in front view.

My present invention is an improvement on the coupler shown and described in my pending patent application, Serial No. 98,473, filed March 17, 1902.

In the drawings, 2 represents the coupler-head, and 3 is the knuckle, whose tail 3' extends rearwardly from the pivot-pin 4, the front side of the tail or the end portion thereof being preferably approximately parallel with the central line of the draw-bar when the knuckle is locked.

The locking and opening piece 5, in so far as its locking function is concerned, is in the nature of a pin which extends on the front side of the tail of the knuckle and in locking has a bearing against the coupler-head, extended both above and below the knuckle. Its lower end is shaped to constitute a tongue or toe b, which is inclined forwardly and is adapted to fit in a correspondingly-inclined hole 6 in the floor of the coupler. Its upper end or head has a forward projection c, or it is otherwise suitably shaped for pivotal attachment to a lifting-link 7, and at the rear of the head is a bearing d, which is adapted to engage a fulcrum 8 at the top of the recess 9 of the coupler-head, in which the piece 5 is

set. This recess is preferably nearly of the same width as the piece 5, so that it may guide and steady the latter. At the rear of the locking and opening piece is a heel e, and on the front it has a lateral extension f, adapted to make initial engagement with the knuckle when the latter is being opened. On the front of the piece 5 are projections h g, with preferably an intervening space between them, and on the under side of the tail of the knuckle is a guard projection i, which prevents the toe b from catching under the knuckle and also imparts the first rearward motion to the piece 5 when the knuckle is moved back. Grooves k k, Fig. 1, are provided in the piece 5 for the discharge of dirt, which might otherwise impair its operation. The lifting-link 7 is pivotally connected in a slot at the top of the piece 5 and is kept upright by a stop-shoulder m at the back of the slot. The link is attached to a chain 11, and the flexibility of the chain and the housing of the link 7 or the greater portion of it within the coupler prevent injury to the lifting mechanism.

The operation is as follows: When the parts are in the position shown at the coupler B in Fig. 2, the knuckle is closed and locked, and the locking and opening piece 5 fits in front of the knuckle-tail, with its toe or guiding portion b in the hole 6, the projection c fitting in a recess n in the coupler-head and the heel e resting on the floor of the coupler and keeping the piece 5 tipped forwardly, so that the projection c thereof will be maintained in the recess. The piece 5 is thus locked and cannot be made to jump or creep upwardly by the jarring of the car. If it be desired to unlock the knuckle and to swing it open, the operator lifts the link 7. This causes the piece 5 to rise, and during its first motion the guiding portion or toe b at its lower end moves it rearwardly until it has passed back of the path of the tail of the knuckle and has left the latter free to swing open and its head has engaged the fulcrum 8 at the top of the coupler-head. The piece 5 is then in knuckle-throwing position, and continued lifting of the link 7 will cause it to tip forwardly on the fulcrum 8, whereupon the projection f will engage the knuckle initially, and the toe b will then move the

knuckle open, as shown in Fig. 4. The operator having thus opened the knuckle can allow the piece 5 to drop into the position shown by dotted lines in Fig. 4. When the 5 knuckle is next swung into closed position, its tail will engage successively the projections *h* and *g* on the piece 5 and will push it back until its toe *b* comes into register with and drops into the hole 6, whereupon the 10 parts will be restored to the locked position above described, and shown at the coupler B of Figs. 1 and 2. If the knuckle has been opened and the locking-piece has accidentally assumed the position shown in coupler B, 15 Fig. 2, while the knuckle was still open, the tail of the knuckle will engage the projections *h* and *g*, and the inclined slot in which the part *b* rests will cause the piece 5 to move rearwardly and upwardly, and this movement will allow the tail of the knuckle to pass, whereupon the locking-piece will again drop into its locked position in front of the tail of the knuckle. If it be desired to unlock the knuckle without throwing it open 20 and to leave the piece 5 in lock-set position, so that the knuckle can be moved open freely when the car to which it is attached is moved away from another car with which it is coupled, the operator simply lifts the piece 5 25 into the position shown at the coupler A of Fig. 2, at which the tail of the knuckle is released. On releasing the lifting-chain, the piece 5 will bear against the end of the tail of the knuckle, the projection *c* will bear against the front wall of the recess 9, and the toe *b* 30 will rest upon the floor of the coupler at 12. There is, however, no locking engagement of the piece 5 with the knuckle, and the knuckle is free to move open when the cars are drawn 35 apart. In moving open, the tail of the knuckle engages the projection *g* and pushes the piece 5 rearwardly somewhat, so as to bring its toe into register with the hole 6, and the piece 5 will then drop back of the knuckle 40 into the same position relatively to the coupler-head which it occupies when the coupler is locked. When the knuckle is next closed, it will engage successively the projections *h* and *g* of the piece 5, whereupon the inclined 45 portion *b* will cause it to rise and move rearwardly and permit the knuckle to pass, and when the knuckle has passed the piece 5 will drop into locking position in front of the tail, as shown at the coupler B in Fig. 2.

50 As a protection against displacement of the knuckle in the event of breaking or loss of the pivot-pin I prefer to form on the rear side of the knuckle-tail near the position of the pivot 4, but not extending to the bottom 55 and top of the knuckle, a recess 13, tapering outwardly toward the head of the knuckle, and to form on the coupler-head near the outer end thereof a projection 14, preferably adapted to enter and interfit with said recess. By locating the recess and projection near the position of the pivot-pin instead of locating them at the inner end of the tail it is easier to fit

them together, and when under draft all tendency of the one to pull away from the other is avoided. Even without the pin the 70 knuckle is held in place with the greatest security. This device also serves to take strain from the pivot-pin when the pin is intact, and thus prevents bending of the pin. By forming the recess in the body of the knuckle 75 and not extending the same to the top and bottom of the rear side thereof the knuckle is not weakened, as it would be if the recess extended from edge to edge of the knuckle. The skilled mechanic will be able to modify 80 the parts of my coupler in various ways, so as to accomplish the results above stated, substantially as I accomplish them by the device shown in the drawings. The locking and opening piece is easy in all its motions and 85 throws the knuckle forwardly to as great extent as desired, and the setting and locking of the lock are performed in a simple and effective manner. The coupler can be made of light weight without sacrificing the strength 90 required in service.

I claim—

1. A coupler having a knuckle, a tipping locking and opening piece having a locking and opening member adapted to fit in front 95 of the tail of the knuckle, and movable to free it from the knuckle, and having a lateral extension adapted to make initial engagement with the rear of the knuckle-tail in opening; substantially as described.

2. A coupler having a locking and opening piece, means for directing it backwardly to free the knuckle, and means for tipping it forwardly to move the knuckle open, said piece having a lateral extension adapted to make initial engagement with the rear of the knuckle-tail in opening; substantially as described.

3. A coupler having a locking and opening piece, said piece having a forwardly-inclined guiding portion at its lower end fitting in a 110 guiding-hole in the floor of the coupler, and constructed to direct the said piece backwardly, and a fulcrum constructed to engage the piece to tip it forwardly, said piece having a lateral extension adapted to make initial engagement with the rear of the knuckle-tail in opening; substantially as described.

4. A coupler having a locking and opening piece, said piece having at its lower end a guiding portion constructed to direct it rearwardly, a lifting device, a locking-recess in the coupler-head forward of the locking and opening piece constructed to receive the head thereof and to hold it in locked position, and a bearing for the said piece adapted to tip it 125 into the recess; substantially as described.

5. A coupler having a locking and opening piece, means for directing it backwardly to free the knuckle, and means for tipping it forwardly to move the knuckle open, said piece 130 being adapted to bear at the upper portion against the coupler-head and at the lower end to rest on the coupler-head when in lock-set position and having a portion adapted to be

engaged by the knuckle in opening; substantially as described.

6. A coupler having an upwardly-movable locking piece, and means adapted to tip it forwardly when it is raised, said piece being adapted to bear at the upper portion against the coupler-head and at the lower end to rest on the coupler-head when in lock-set position, and having a portion adapted to be engaged by the knuckle in opening; substantially as described.

7. A coupler having a locking and opening piece, said piece having a forwardly-inclined guiding portion at its lower end fitting in a guiding-hole in the floor of the coupler and constructed to direct the said piece backwardly, and a fulcrum constructed to engage the upper end of the piece to tip it forwardly, said piece having projections *h*, *g*, adapted to be engaged by the knuckle; substantially as described.

8. A coupler opening and locking piece upwardly and rearwardly movable and having on its forward side projections *h* and *g* adapted to engage the knuckle successively; substantially as described.

9. A coupler-lock having on the lock a stop adapted to bear on the rear side of a lifting-

link and to support the same; substantially as described.

10. A coupler-lock having a lifting-link pivoted in a slot in said lock, and a stop in the slot on the rear side of the link for supporting the same; substantially as described.

11. A coupler-knuckle having on the under side of its tail a guard projection *i*, adapted to coöperate with a tipping opening member; substantially as described.

12. In a coupling, the combination with a coupling-head and a pivoted knuckle having a tail to enter the head, of a locking-block having a seat in the head and against the end of the tail to lock it in the head, a pivoted support for the block, a tongue or finger carried by the block, an enlargement in the coupling-head, and an inclined arm at the upper end of the block to fulcrum on the enlargement, tilt the block and compel the tongue or finger to eject the knuckle, when the support is elevated.

In testimony whereof I have hereunto set my hand May 26, 1902.
